UNITED STATES PATENT OFFICE.

KARL WENDT, OF GEORGSMARIENHÜTTE, NEAR OSNABRÜCK, GERMANY, ASSIGNOR
TO THE FIRM OF GEORGSMARIEN-BERGWERKS- UND HÜTTEN-VEREIN, AKTIEN-
GESELLSCHAFT, OF GEORGSMARIENHÜTTE, NEAR OSNABRÜCK, GERMANY.

FURNACE WITH REGENERATIVE FIRING.

1,097,900.

Specification of Letters Patent. Patented May 26, 1914.

Application filed December 14, 1911. Serial No. 665,755.

To all whom it may concern:

Be it known that I, KARL WENDT, a citizen of the German Empire, residing at Georgsmarienhütte, near Osnabrück, Germany, have invented certain new and useful Improvements in Furnaces with Regenerative Firing, of which the following is a specification.

The rolling mill furnaces used heretofore for heating ingots were constructed either as furnaces with fixed flame direction or as Siemens regenerators with alternating flame direction. The advantage of the former consists in the ingots being placed in the furnace at the front side by means of a feeding apparatus, and gradually pushed forward into the hottest zone. This gradual heating of the ingots is especially necessary in the case of hard-steel ingots, apart from the fact that the cinder and waste is thereby reduced. These furnaces are usually heated by grate-firing. Gas-firing can only be carried out to advantage with a gas of great calorific value or in such cases where the ingots do not need to be subjected to great heat. The advantage of regenerative firing, on the other hand consists in it being possible to heat the furnace with inferior gases, apart from the fact that the attendance of such gas-firing plants is extremely simple. They have, however, the disadvantage, in the designs heretofore employed in which the air-channels are arranged in the front wall of the furnace, that the ingots require to be placed in the furnace through the side-doors in separate lots by means of expensive charging apparatus, thereby being immediately introduced into the very hot furnace without being previously warmed.

The object of the present invention is to unite the advantages of both systems in a furnace with regenerative gas firing by a novel arrangement of the burners and the feed-track. For this purpose the burners are placed on one or both sides in the sole or hearth, so that the front walls remain free for the introduction of the ingots. The latter glide along an uncovered feed-track consisting for example of water-cooled pipes, between which the heating channels are arranged. In order to prevent the ingots being immediately subjected to great heat by the hot gases which pass out on the charging side, the heat channels near the

charging door are covered with vaulted masonry, so that the ingots are warmed before they come into direct contact with the gases. The gas and air supply of the burners on the charging side is so constructed that the complete combustion of the mixture of gas and air only takes place after having passed through a certain path in the furnace, thus insuring the maximum heat always at the same place, i. e., near the discharge-opening. Various forms of this apparatus are shown in the drawings.

Figure 1 shows a longitudinal section of a furnace with feed-track extending from end to end. Fig. 2 shows a section at the line 2-2 in Fig. 1. Fig. 3 shows a longitudinal section of a modified furnace with feed-track and rolling bed. Fig. 4 shows a section on the line 4-4 in Fig. 3. Fig. 5 is a section on the line 5-5 of Fig. 1; and Fig. 6 is a section on the line 6-6 of Fig. 3.

The index letters of all the drawings are employed for the same parts throughout.

In Figs. 1 and 2 the furnace is shown with a feed-track extending from end to end, on which the ingots are pushed through the furnace by a feeding device C. A is the charging side, v the feed-track with cooling water-pipes. The pipes together with the feed-track v bear on the supporting walls y, (see Fig. 2) between which the channels o, p, q, r, s are arranged, through which gas and air are passed in such proportions that complete combustion takes place and consequently the greatest heat is developed near the discharge-opening.

a and b are the air or gas channels on the discharge side B, c and d those on the charge-side. These channels are connected up to the regenerative chambers e, f, g and h. The channels a and b lead to the burner G¹, and the channels c and d to the burner G². The two burners G¹ and G² are situated in the sole or hearth.

The regenerator h may be connected to the furnace chamber by an additional flue i having a port k, through which air is admitted, thereby causing the greatest heat to be developed within the furnace not too far from the exit B.

The heat channels o, p, q, r and s are covered by protective covering of vaulted masonry at the burner G² on the charge-side, so that the ingots are warmed to some ex-

tent before coming in contact with the heating gases. The supply of gas and air at this point is so designed that the complete combustion of the mixture of gas and air cannot take place until after a certain path has been traveled by the gases, in the furnace, thus insuring the greatest heat always being developed at the same point, *i. e.* near the discharge-opening B.

10. The process in the furnace takes place as follows:—The gases issuing from burner G^1 play at first on the ingots m near the discharge opening B, giving the already thoroughly heated ingots their maximum grade of heat. After heating the same and warming the other inserted ingots m' , the gases leave the furnace by passing through the vaulted masonry n through the passages into the chambers g and h . After the change in 15 the direction of the flames, air and gas pass through the channels c and d into the space below the vaulted masonry n and divided by the supporting walls y into the single channels o , p , q , r and s . The slag formed is 20 drawn off through the channels u and t .

In the furnace shown in Figs. 3 and 4, the feed-track v is connected up direct to an inclined bed w , on which the ingots m , are gradually rolled to the discharge-opening B. 25 In this type of furnace the discharge opening is placed at the side, and therefore the burner G^2 only is necessary on one side of the sole or hearth. The burners G^3 ending in the lateral channels o and s are hereby 30 partially or wholly moved back into the side-walls of the furnace (see Fig. 4), as in this case the feeding of the ingots from the front is not impeded. In order to secure the development of the maximum degree of heat 35 near the discharge-opening there may also be installed additional gas and air burners suitably distributed in the sole or hearth and the side-walls of the furnace.

Poker bars may be inserted in opening z 40 in Fig. 3 to assist in moving the ingots forward. The regenerator h may also be connected to the furnace chamber by an additional flue i' having a port k' as in Fig. 1.

What I claim as my invention and desire 45 to secure by United States Letters Patent is:—

1. A furnace having gas and air regenerators at each end, gas and air conduits connected to said regenerators and arranged to 50 deliver the flame into the furnace at each end and longitudinally thereof in either direction, said furnace having a charging opening in its end wall, a feed track extending from said opening into the furnace, and a

protective covering located beneath the end 60 portion of the track and spaced from the bottom of and extending part way into the furnace to form a longitudinal flue or flues, the gas and air conduits at the charging end of the furnace connecting the regenerators at that end to such flue or flues, said flue or flues constituting the outlet for the products of combustion when the flame is reversed.

2. A furnace having gas and air regenerators at each end, gas and air conduits connected to said regenerators and arranged to deliver the flame into the furnace and longitudinally thereof, said furnace having a charging opening in its end wall, a feed 70 track extending from said opening into the furnace, a protective covering located beneath the charging end portion of the track and spaced from the bottom of the furnace to form a longitudinal flue or flues, the gas 75 and air conduits at the charging end of the furnace connecting the regenerators at that end to such flue or flues, and additional gas and air conduits connecting the charging-end regenerators with ports located in the 80 side walls of the furnace above said protective covering.

3. A furnace having gas and air regenerators at each end, gas and air conduits connected to said regenerators and arranged to 90 deliver the flame into the furnace at each end and longitudinally thereof in either direction, said furnace having a charging opening in one end wall, a feed track extending from said opening into the furnace, 95 a discharging opening, and means to deliver the flame from one end into the furnace at a point distant from said end and toward the middle of the furnace.

4. A furnace having gas and air regenerators at each end, gas and air conduits connected to said regenerators and arranged to deliver flame into the furnace and longitudinally thereof, said furnace having a charging opening in its end wall, a discharge 100 opening at a distance from said charging opening, means to convey an article to be heated through said furnace and a supplementary air conduit arranged to supply a blast of air to a flame at a point along the 105 length of said flame.

In testimony whereof I affix my signature in presence of two witnesses.

DR. KARL WENDT.
